[57] CLAIM

The ornamental design for an electronic calculating machine, as shown and described.

DESCRIPTION

FIG. 1 is a perspective view of an electronic calculating machine showing my new design;

FIG. 2 is a top plan view thereof;

FIG. 3 is a front elevational view thereof;

FIG. 4 is a left side elevational view thereof;

FIG. 5 is a right side elevational view thereof;

FIG. 6 is a rear elevational view thereof; and

FIG. 7 is a bottom view thereof.

The broken line display of the numerals in FIG. 1 is for illustrative purposes and forms no part of the claimed design.
